UNITED STATES PATENT OFFICE.

JOHN G. ENGELHART, OF ATLANTA, GEORGIA, ASSIGNOR OF ONE-HALF TO LEWIS F. OSTRANDER, OF ST. LOUIS, MISSOURI.

QUICK-OPENING PACKLESS VALVE.

1,226,485.

Specification of Letters Patent. Patented May 15, 1917.

Application filed August 5, 1912. Serial No. 713,394.

To all whom it may concern:

Be it known that I, JOHN G. ENGELHART, a citizen of the United States, and resident of Atlanta, Fulton county, Georgia, have invented certain new and useful Improvements in Quick-Opening Packless Valves, of which the following is a specification containing a full, clear, and exact description, reference being had to the accompanying drawings, forming a part hereof.

My invention relates to improvements in quick-opening packless valves, and is designed with special reference to radiators.

The object of my invention is to provide an improved construction of radiator valves in which there is a means provided with a stem for positively and rapidly moving the valve proper to seat or unseat and in which there is permanent packing devices around said stem, thereby obviating the necessity of "packing" the valve.

With the above purposes in view my invention consists in certain novel features of construction and arrangement of parts as will be hereinafter more fully described, pointed out in the claim and illustrated by the accompanying drawings, in which—

Figure 1 is a vertical, sectional elevation of a complete valve; and

Fig. 2 is a sectional plan taken through the valve and its stem.

Referring by numerals to the accompanying drawings:

3 designates the globular body portion of the valve provided with an internally threaded inlet 4 for connection with a supply pipe and an externally threaded outlet 5 for connection with a radiator (not shown).

At the upper end of the globular body 3 there is a neck 6 alining with the inlet 4 and which is internally screw threaded to receive the bonnet 7.

The bonnet 7 is formed hollow throughout its length, and at its lowermost end is provided with an internal thread 8 which receives and supports the valve proper 9 which is externally threaded and which is formed with a non-circular socket for a portion of its length in order to receive the non-circular portion 10 of the valve-stem 11. In other words, the said valve has an angular socket, and said stem has an angular shank which engages said socket.

Formed in the bonnet 7 above the thread

8 is a ground-joint 12 which receives the conical portion of the stem and, formed in the bonnet above the conical ground-joint 12 is a guide 13 which bears against the stem 11 and serves to hold the stem in a true position.

Formed in the bonnet above said guide 13 is a stuffing-box 14, the lowermost end of which inclines downwardly and inwardly toward the stem 11.

15 designates a compressible-fiber packing, and 16 designates an extensible coil spring which bears upon the packing 15.

17 designates a handle in which is formed, on its underneath face, an annular channel 18 in which there is located a packing-ring 19 which rests upon the upper end of the bonnet with the channel embracing the upper end of the bonnet.

The upper end of the stem is squared at 20, and the handle 17 is provided with a squared-opening to embrace the squared portion of the stem.

21 designates a screw which is arranged to secure the handle against vertical movement relative to the stem.

22 designates washers arranged at either end of the spring 16 so as to prevent wearing between the spring and the parts of the valve engaged thereby.

The lowermost end of the valve proper 9 is chamfered to form a cone 23 which is arranged to fit the seat 24 in the body portion above the inlet 4.

In order that there be a clearance between the opening in the valve proper and the squared portion 10 of the valve-stem for free movement of the valve proper vertically relative to the stem, the stem is formed rectangular at 10, while the opposing walls of the opening in the valve proper are convex or curved as shown in Fig. 2, and bear against said stem only at the approximate centers of the facets of the stem, so that there is a minimum of bearing surface between the valve proper and the stem.

Assuming the parts to be in the positions shown in the drawings, it will only be necessary to rotate said handle 17 to close or open the valve 9, as it is to be observed that the stem is provided with a conical portion and has connected thereto a handle, and that there is an extensible coil spring which bears upwardly against the handle, thereby holding the cone seated to form a

fluid-tight joint to prevent the escape of fluid upwardly through the bonnet and around the stem.

It is to be observed further that the said spring bears downwardly against a fiber packing and compresses it against the stem around a circular portion of the stem. This fiber packing automatically adjusts itself to wear, that is in case there is wear the spring will always hold the packing to form a fluid-tight joint around the stem.

The said spring 16 not only holds the packing so that same will be automatically adjusted, as just described, but the spring 15 also presses upwardly upon the said washer 22 beneath the handle 17, and thereby holds said handle's packing-ring 19. (and said handle) up, and prevents too close fit, and consequent excessive friction, between the 20 said packing-ring and the upper edge of the said bonnet.

I claim:

An improved quick-opening valve, comprising a suitable body having the usual 25 inlet and outlet and valve-seat; a valve-stem; a valve loose upon said stem so that it may move vertically thereon, but arranged

to rotate therewith; a bonnet mounted upon said body; a threaded-connection between said valve and said bonnet; a cone on said stem above said valve; a seat for said cone, formed in said bonnet; a body of packing in said bonnet, above said cone; a handle secured to the upper end of said stem, and having an annular channel in its underside; a packing-ring located in said channel of the handle, and resting in contact with the upper end of said bonnet, with the walls of said channel embracing the upper end of said bonnet; a washer beneath said handle, within the upper end of said bonnet; and a coil spring surrounding the said valve-stem, and bearing down upon said packing, and bearing upward upon said handle washer, and tending to lift the handle off 45 the bonnet.

In testimony whereof, I have signed my name to this specification, in presence of two subscribing witnesses.

JOHN G. ENGELHART.
